CLAIM

The ornamental design for a toilet seat and cover combination, as shown & described.

DESCRIPTION

FIG. 1 is a top plan view of a toilet seat and cover combination showing my design. The cover shown in open position;

FIG. 2 is a left side elevation view thereof. The broken line showing toilet seat fastener is for illustrative purposes only and forms no part of the claim design;

FIG. 3 is a front elevation view thereof;

FIG. 4 is a bottom elevation view thereof;

FIG. 5 is a rear elevation view thereof;

FIG. 6 is a right side elevation view thereof;

FIG. 7 is a top plan view of a toilet seat and cover combination similar to FIG. 1 showing the cover in closed position; and,

FIG. 8 is a left side elevation view thereof.
